UNITED STATES PATENT OFFICE.

ANTHONY S. BUSK, OF WOODHAVEN, NEW YORK, ASSIGNOR TO R. HOE AND CO., OF NEW YORK, N. Y., A CORPORATION OF NEW YORK.

SHEET-REGISTERING MECHANISM FOR TIN SHEETS.

1,321,807.

Specification of Letters Patent. Patented Nov. 18, 1919.

Application filed March 7, 1917. Serial No. 153,150.

To all whom it may concern:

Be it known that I, ANTHONY S. BUSK, a citizen of the United States, residing at Woodhaven, county of Queens, and State 5 of New York, have invented certain new and useful Improvements in Sheet-Registering Mechanism for Tin Sheets, fully described and represented in the following specification and the accompanying drawings, forming a part of the same.

This invention relates to certain improvements in feeding mechanism for heavy sheets, and particularly tin sheets and the like, which are to be printed upon.

15 Difficulty has been experienced in securing accurate registry of sheets of tin, because of the irregularity in the dimensions of the sheets as commercially produced. This difficulty in registration is particularly 20 disadvantageous in the case where the sheets are printed with multiple impressions, as in printing thereon multi-color designs.

The invention has for its especial object the provision of a simple mechanism for 25 both front registering and side registering of these heavy sheets, so that the sheets are accurately positioned and their positions maintained until securely taken by the sheet-taking devices of the printing machine.

30 It is a further object of the invention to provide a front and side registry device which operates without rubbing the surfaces of the tin sheets during the registry operation.

35 A full understanding of the invention can best be had by a detailed description of the same, which will now be given in connection with the accompanying drawings, in which—

40 Figure 1 is a side elevation, partly in section, of the improved feeding and registering mechanism, shown as feeding to a rotary printing couple, the impression cylinder of which is provided with sheet taking 45 grippers;

Fig. 2 is a plan view of part of the mechanism shown in Fig. 1, the plan being taken on line 2—2 of Fig. 1, the frame of the machine being shown in section;

50 Fig. 3 is a plan view of a portion of a train of the feeding rolls feeding the sheet up to the registry devices;

Fig. 4 is an enlarged detail view, partly

in section, of the side registry devices, the view being taken on line 4—4 of Fig. 2; 55

Fig. 5 is a detail view of the front registry rolls, partly in section and partly broken away, the view being taken on line 5—5 of Fig. 1, and

Fig. 6 is an end view of part of the construction shown in Fig. 5, the view being taken looking in the direction of the arrow x, and

Fig. 7 is a diagrammatic view of the front stops and grippers carried by the impression cylinder.

Referring now to the drawings, the invention has been shown as feeding to a printing machine, the members of the printing couples of which are cylinders, although it will be understood that the invention is intended to, and may, be used with other forms of printing mechanism. In the drawings, the form cylinder is indicated by the numeral 1 and the impression cylinder 70 by the numeral 2, this cylinder being provided with sheet-taking devices. Acting with the impression cylinder are the usual front stops 3. Where, as in the present instance, the sheet-taking devices are grippers, 80 these front stops are mounted on the shafts 4 of the grippers 5, these being operated in any usual or desired manner.

Machines embodying the invention will 85 include front and side registering mechanism, and mechanism which acts to feed or forward the sheets to the registering mechanism. While these feeding and forward- 90 ing means may be of various character, in the machine illustrated they are in the form of a table of rolls 6, suitably journaled in side frames 7, which are driven at the same surface speed as the impression cylinder 95 through any suitable means, as from large gear 8 mounted on shaft 9 extending across the machine, this shaft 9 being driven at cylinder speed through suitable gearing (not shown). The gear 8 meshes with and drives a gear 10 mounted on a short shaft 10' in suitable bearings in a bracket supported 100 from the main frame A of the machine, this shaft carrying a gear 12 at its inner end which meshes with intermediate gear 13 which in turn mesh with gears 14 on one of the rolls 6, the train of rolls being driven 105 through the gears 14 and train of inter-

mediate gears 15 extending the length of the roll table. Side guides may be provided along the train of rolls, if desired, which may be in the form of rolls 16 carried on 5 studs 17 rising from a bar 7' secured to the frame 7 before referred to. The sheet of tin or other material to be fed and registered is delivered to these rolls 14 from a suitable source of supply by means of feed- 10 ing-in rolls (not shown), and the rolls 6 act to feed or forward the tin to the registering mechanism.

Machines embodying the invention in its preferred form are designed to produce 15 accurate registry of tin or other material, the shape of which is somewhat irregular due to inaccurate cutting, some sheets, for instance, varying in width by a half of an inch or more from the head to the tail of 20 the sheet, and these irregularities are taken care of by the improved registering mechanism. Unless this irregularity in the sheet is taken care of, as the sheet is being forwarded to the taking devices of the printing mechanism, the sheet would be liable 25 to be thrown out of register. Machines embodying the invention, therefore, will include register devices which will take care of this irregularity in the sheet, so that the 30 sheet will have perfect register until positively taken by the sheet taking devices. While the particular construction for effecting this may be somewhat varied, there is provided a set of what may be termed forward- 35 warding and registering rolls, this set including a lower metal roller 20 and a pair of upper forwarding rolls 21, 22. These rolls are driven at the speed of the impression cylinder, being driven in the particu- 40 lar construction illustrated by the large gear 8, before referred to, meshing with a gear 23 on the shaft 24 of the bottom roll 20. Where, as is usually the case, the sheet-taking 45 devices of the printing couple are grippers, it may happen that the closing action of the grippers on the sheet will have a tendency to retard the sheet from forward movement. In machines, therefore, where the registering and forwarding de- 50 vices are rolls, the upper rolls will be driven so that they will stop when the forward movement of the sheet stops, so as to avoid rubbing of the sheet. While this may be effected in various ways, the upper leather- 55 covered rolls 21, 22 are driven from a shaft 25 through a torsion spring 26 taken between a collar 27 and a gear 28, this gear 28 being in mesh with and driven from the gear 23, before referred to. With this construc- 60 tion, the rolls 21, 22 are driven at cylinder speed, but through the spring connection, they will be allowed to stop when the tin stops.

In machines embodying the invention employing these superposed rolls, the rolls are,

for purposes hereinafter referred to, supported so that they can partake of a side- 70 wise or transverse movement relatively to the sheet path. In the best constructions, furthermore, where the rolls are employed in superposed sets, the upper rolls are supported so that they may press upon the sheet with varying pressures, to compensate for different thicknesses in the tin sheets. While this may be done in various ways, 75 this pressure is preferably a spring pressure, means being provided for adjusting the spring. In the particular construction illustrated, the shaft 25, before referred to, is supported from depending brackets 29 80 hung from studs 30 in suitable cross-pieces 31 extending across the machine and supported in the main frame thereof. A suitable number of these brackets are provided along the shaft, and the shaft is connected 85 to the brackets so that it may have a movement relatively thereto to permit a movement transverse to the sheet path. As illustrated, the shaft 25 has fast thereon hubs 32 pivotally connected by pins 33 to blocks 90 34 secured to rods 35 held in ears or extensions 36 formed on the brackets, this construction permitting the movement referred to. As before stated, in the best constructions the rolls are held by pressure against 95 the tin sheets, this pressure being variable within the necessary limits. As shown, the springs 37 are provided on the rods 35, before referred to, these springs being located between the upper ears or extensions 36 of 100 the bracket and collars or stops 38 secured to the rolls 35. Adjustment may be given these springs by suitable adjusting nuts 39.

With the construction so far described, the sheets forwarded from the table rolls 105 are taken by the registering rolls and forwarded up against the front stops of the sheet-taking devices of the impression cylinder. While the sheets are thus being forwarded by the registering rolls, they are 110 registered sidewise, that is, given a side register, and are preferably held side registered until after the sheets have been taken by the grippers or other sheet-taking devices of the sheet-taking cylinder. Owing to the 115 irregularity in the widths of the sheets of tin, the sheets are liable to be thrown out of register as they are taken by the sheet-taking devices. In machines embodying the invention in its best form, therefore, 120 means are provided whereby this irregularity can be compensated for. While the specific construction for effecting this may be somewhat varied, in the construction shown the forwarding and registry rolls are 125 so mounted that they may have a yielding sidewise movement, or movement transverse to the sheet path, being moved by the movement of the sheet. In the particular construction illustrated, this is effected by con- 130

necting the shafts 24, 25, before referred to, with short shafts 40, 41, respectively, these short shafts being slidably mounted in bearings 42 in the main frame of the machine. These shafts 24, 25 are, furthermore, so connected as to have this transverse movement together. In the particular construction illustrated, this is effected by an anchor plate 43 secured by suitable bolts 44 on the ends of the shafts. In the best constructions, this transverse movement of the shafts is a yielding movement which is conveniently effected by a spring 45 carried on a rod 46 provided with a collar 47 taking into a yoked arm 48 pivoted on a bracket 49 suitably secured to the machine frame.

With this construction it results that when the sheet is moved to side register, the rolls are, through the medium of the sheet, fed transversely of the sheet path with the sheet, and this movement being a yielding one against the spring, the rolls tend to hold the sheet against the side registry devices. Irregularities of the sheet as to width, therefore, the sheet having once been side registered, do not tend to force the sheet out of such registry.

The particular form of side registry devices for the sheets may be varied, but in the preferred construction there will be such devices on each side of the sheet path which may be independently operated so that either side of the machine may be employed. While these side guides or registry devices may vary somewhat in construction, they will be duplicated on each side of the machine, and those on but one side will be described. As illustrated (see Figs. 2 and 4), they include flat plates 50 forming a support for the sheet beyond or outside the ends of the rolls, and small side registry rolls 51 horizontally disposed and secured by bolts 52 to guide blocks 53, these blocks 53 having wings 54 acting as guides. The plates 50 and blocks 53 are carried in blocks 55, which are or may be feathered on the ends of the roll shaft 24, before referred to, so as to have a sliding movement thereon. These rolls 51 are moved to side register the sheet, the blocks supporting them being operated in any suitable manner to bring the sheets into their proper registered position. The particular connections for thus operating the blocks may be somewhat varied, but in the particular construction shown each block will be operated from side guide cams 56 keyed or otherwise mounted to slide on the shaft 9 before referred to, the cams being held in position by cam yokes 57. These cams operate a cam lever 58 pivoted at 59 in an extension 60 projecting from the cam yokes 57. This cam lever 58 carries a cam roll 61 operating in a cam groove 62 of the cam. Connected with this cam roll lever 58

and operated thereby is a side guide lever 63, this lever being provided with a slot 64 at its end (see Fig. 2) in which works a stud 65 secured to the block 55, before referred to.

When the machine is operating to side register a sheet these two levers 58, 63 work as one to cause the operation of the side guides as described. As it is desirable to operate only one side of the machine at a time, however, the connections between the levers are such that the side guide levers 63 on either side of the machine may be silenced to stop its operating movement, the movement of the lever 58, because of the cam, necessarily continuing. While these connections may be of any suitable character, in the construction illustrated the levers are superposed, and at their outer ends, as shown in Fig. 1, are connected together by a stud 66 working in the slot 67 in the lever 63 and in an opening 68 formed in an enlargement 69 on the end of lever 58. With this construction, by loosening the stud and moving it from the position shown in Fig. 2, to the end of the slot 67, the stud can work in the large opening 68 in the end of lever 58, thereby causing the operative movement of lever 63 to cease. The cam 56 before referred to may be backed by the usual spring rod construction 81, part of the rod construction being shown in Fig. 2.

Machines embodying the invention in its best form will include means whereby the throw of the cam, and, consequently, the movement of the side registry devices, may be varied to provide for the side registry of sheets of different widths, and preferably this adjustment of the cam will be such that it can be done while the machine is in operation. Furthermore, the adjusting mechanism will be such that the side guide cams on each side of the machine may be adjusted from a single adjusting mechanism located on one side of the machine. While mechanisms of different character may be employed for effecting these purposes, in the particular construction illustrated there are provided two adjustable shafts 70, 71. These shafts are threaded and pass through the extensions 60 of the cam yokes 57, before referred to, which are threaded to receive them. The shaft 70 is supported at one end by a bearing 72 in the main frame of the machine and at its other end is supported in a bearing in the center of the machine, indicated at 73 in Fig. 1. This shaft 70 adjusts the cam at the left hand side of the machine, looking at Fig. 2. The right hand cam at the right hand end of the machine, is adjusted from the shaft 71, which may be given an adjusting movement independent of the shaft 70. In the particular construction shown, the shaft 71 is supported by the shaft 70, the shaft 70 being

sleeved to permit the shaft 71 to pass therethrough. The mechanism for adjusting the shaft 70 may include a hand wheel 75 on a short shaft 76 mounted in a frame 77 supported from bearings 72, before referred to. This shaft is provided with a sliding gear 78 meshing with a gear 79 on the shaft 70. The shaft 71 may be independently operated from the gear 80 mounted on the end 10 of the shaft which projects beyond the shaft 70. This gear 80 is operated by sliding gear 78 pulling gear 78 out of mesh from gear 79 and into mesh with gear 80.

In the operation of the machine, the sheet 15 is forwarded by the table rolls 6 up to the registering and forwarding rolls 20, 21 and 22. As the sheet is in the control of these rolls, the side guide mechanism is operated, it being moved sidewise in toward the sheet 20 until the edge of the sheet is touched by the small roller 51 of the side guide devices. The side guide is then moved a little farther sidewise through the proper timing of the cam, but the sheet, instead of sliding between 25 the rollers, acts to carry the rollers sidewise with the tin; as both the rollers are secured together and move simultaneously through the anchor plate 43, backed by the spring 46, the sheet has a yielding pressure against the 30 side guide which keeps the sheet in perfect side register, and as the side guide is held against the sheet by the timing of the cams until the grippers are closed and the sheet positively taken, the side register of the 35 sheet is insured, even if it is somewhat irregular.

While the invention has been shown and described in its preferred form, it will be understood that wide changes and variations 40 may be made in the specific construction for carrying the invention into effect, and it will be further understood that while the invention has been particularly designed for the feeding of tin sheets, more or less irregular 45 in dimensions, it may be used for feeding other irregular sheets of heavy material.

What is claimed is:—

1. In a mechanism for feeding and registering heavy sheets, the combination of front 50 registering devices, means acting on the surface of the sheet for forwarding the sheets thereto for front registering, side registering devices movable sidewise of the sheet path for side registering the sheet as it 55 moves forward, and means for holding the sheet against the side registry devices under a yielding pressure during its forward movement.

2. In a mechanism for feeding and registering heavy sheets, the combination of front 60 registering devices, devices for forwarding the sheets thereto for front registry, side registry devices movable sidewise of the sheet path for side registering the sheet, and 65 means whereby the sidewise movement of

the sheet causes a sidewise movement of the forwarding devices.

3. In a mechanism for feeding and registering heavy sheets, the combination of front 70 registering devices, devices for forwarding the sheets thereto for front registry, side registry devices movable sidewise of the sheet path for side registering the sheet, means whereby the sidewise movement of the sheet causes a sidewise movement of the 75 forwarding devices, and resistance means against which the forwarding devices move sidewise.

4. In a mechanism for feeding and registering heavy sheets, the combination with an 80 impression cylinder having front registering devices, of sheet taking devices on the cylinder, means acting on the surface of the sheet for forwarding sheets to the front registry devices, side registry devices movable sidewise of the sheet path for side registry of the sheet, and means whereby the sheet is held against the side registry devices under a yielding pressure during its forward movement and until it has been 85 taken by the sheet taking devices on the cylinder.

5. In a mechanism for feeding and registering heavy sheets, the combination of an 90 impression cylinder having sheet taking grippers, front registering devices, devices acting on the surface of the sheet for forwarding sheets thereto for front registry, means for driving the forwarding devices at cylinder speed, side registering devices 95 100 for registering the sheets sidewise as they move forward, and means whereby the forwarding action of the forwarding devices may be caused to cease when the sheet is taken by the grippers.

6. In a mechanism for feeding and registering heavy sheets, the combination of front stops, superposed forwarding rolls for forwarding the sheets thereto, means for driving one of the rolls at cylinder speed, means 110 for driving the co-operating roll at cylinder speed, means whereby the drive of one of the rolls may be interrupted when a sheet stops, and side registry devices for side registering the sheet.

7. In a mechanism for feeding and registering heavy sheets, the combination of front stops, a lower forwarding roll driven at cylinder speed, a pair of upper forwarding rolls, a shaft therefor, a gear for driving 115 the shaft from the lower roll at cylinder speed, a spring interposed between the gear and shaft through which the shaft is driven for causing the upper rolls to stop when a sheet is stopped, and side registering devices 120 for side registering the sheets.

8. In a mechanism for feeding and registering heavy sheets, the combination of front 125 registering devices, upper and lower forwarding rolls for forwarding sheets thereto, 130

side registering devices movable sidewise of the sheet path for side registering a sheet, means connecting the rolls for causing them to be moved sidewise simultaneously by the 5 sheet, and resistance means acting to resist sidewise movement of the rolls.

9. In a mechanism for feeding and registering heavy sheets, the combination of front registering devices, superposed for 10 forwarding rolls for forwarding the sheets thereto, shafts for the rolls slidable sidewise of the sheet path, connections for causing the shafts to move sidewise in unison, means yieldingly holding the shafts against 15 sidewise movement, and side register devices for side registering the sheet.

10. In a mechanism for feeding and registering heavy sheets, the combination of front 20 registry devices, superposed rolls for for- 25 warding sheets thereto, shafts for the rolls slidable sidewise, a plate connecting the shafts, a spring for causing the plate to have a yielding sidewise movement, and side register devices for side registering the sheet.

11. In a mechanism for feeding and registering heavy sheets, the combination of front registering devices, devices for for- 30 warding the sheets thereto for front regis- 35 try, said devices also having a yielding movement sidewise of the sheet path, side registry devices for side registering the sheet located on each side of the sheet path, and means whereby either one of the side 40 registry devices may be rendered inoperable.

12. In a mechanism for feeding and registering heavy sheets, the combination of front registering devices, devices for forwarding sheets thereto for front register, side regis- 45 50 try devices located on each side of the sheet path, means whereby either one of the sheet

registering devices may be rendered inoperable, and means for adjusting either of the sheet registry devices from one side of the sheet path.

13. In a mechanism for feeding and registering heavy sheets, the combination of front 50 registering devices, devices for forwarding the sheets thereto for front registry and having a yielding sidewise movement trans- 55 verse of the sheet path, side register devices including register rolls located on each side of the sheet path and movable sidewise thereof for side registering the sheet, and means for operating either one of the side 60 registry devices as the sheet is forwarded.

14. In a mechanism for feeding and registering heavy sheets, the combination of front 65 registering devices, devices for forwarding sheets thereto for front registry, side regis- 70 tering devices movable sidewise and located on each side of the sheet path, a cam and cam levers, one for each side registry device, and means for adjusting either of the cams sidewise from one side of the sheet path.

15. In a mechanism for feeding and registering heavy sheets, the combination of front registering devices, devices for for- 75 warding sheets thereto for front registry, side registering devices movable sidewise and located on each side of the sheet path, a cam and cam levers, one for each side regis- 80 try device, a shaft operatively connected to one of the cams, a second shaft operatively connected to the other of said cams, and means for adjusting either of the shafts 85 sidewise from the same side of the sheet path.

In testimony whereof, I have hereunto set my hand.

ANTHONY S. BUSK.
